US00D858572S

(12) **United States Design Patent** (10) Patent No.: **US D858,572 S**
(45) Date of Patent: ** Sep. 3, 2019

(54) **DISPLAY SCREEN OR PORTION THEREOF WITH ICON**

(71) Applicant: **Palantir Technologies Inc.**, Palo Alto, CA (US)

(72) Inventors: **Piotr Kwiatkowski**, London (GB); **Antoine Llorca**, San Francisco, CA (US)

(73) Assignee: **PALANTIR TECHNOLOGIES INC.**, Palo Alto, CA (US)

(**) Term: **15 Years**

(21) Appl. No.: **29/646,046**

(22) Filed: **May 1, 2018**
